Primary Examiner — Robert M Spear(74) *Attorney, Agent, or Firm* — Standley Law Group LLP(57) **CLAIM**

The ornamental design for a container cover, as shown and described.

DESCRIPTION

FIG. 1 is a top perspective view of the container cover; FIG. 2 is a bottom perspective view of the FIG. 1 system; FIG. 3 is a top elevation view of the FIG. 1 system; FIG. 4 is a left side elevation view of the FIG. 1 system; FIG. 5 is a bottom elevation view of the FIG. 1 system; FIG. 6 is a right side view of the FIG. 1 system; and, FIG. 7 is a cross section view of the FIG. 1 system. Broken lining visible in FIGS. 1, 3, and 7 denote a circular area located on the top surface of the container cover. This area depicts environment and forms no part of the claim.

1 Claim, 2 Drawing Sheets---
